UNITED STATES PATENT OFFICE.

WILLIS C. LEE AND MILES F. MOORE, OF CHICAGO, ILLINOIS.

RAIL-CLAMP.

SPECIFICATION forming part of Letters Patent No. 703,430, dated July 1, 1902.

Application filed November 30, 1901. Serial No. 84,256. (No model.)

To all whom it may concern:

Be it known that we, WILLIS C. LEE and MILES F. MOORE, citizens of the United States, residing at Chicago, in the county of Cook and State of Illinois, have invented a new and useful Rail-Clamp, of which the following is a specification in its best form now known to us, reference being had to the accompanying drawings, in which similar characters indicate the same parts throughout the several views.

Our invention relates to clamps for use on railroad-rails, and particularly to a clamp for securing the guard-rail to the main rail. For convenience in description it is therefore shown and will be described as a guard-rail clamp; but this is not to be construed as limiting or narrowing the scope of the invention.

The object of our invention is to secure the guard-rail to the main rail at any desired point by an adjustable fastening which will when loosened permit of the distance between the rails being varied and which when tightened will hold the rails securely in the desired position, while maintaining the vertical center lines of the rails substantially parallel.

One great objection to guard-rail clamps heretofore used is that most, if not all, of them have been so constructed that as they are tightened the tops of the rails are sprung away from each other into a position which is not desired and which frequently causes accidents to trains.

Our invention consists in a clamp capable of accomplishing the above objects and having the above advantages which can be easily and cheaply constructed and applied to the rails.

It also consists in other advantages in details of construction, hereinafter more fully described and claimed.

In the drawings, Figure 1 is a side view, partially in section, of a clamp, illustrating our invention applied to a rail and guard-rail of the usual construction. Fig. 2 is a plan view of the same, and Fig. 3 is a detail view of a main spacing-block or separator.

Again referring to the drawings, the number 10 indicates the main rail, and 11 the guard-rail. Embracing the outer flanges 12

and 13 of these rails are the two clamp-jaws 15, preferably made of malleable iron or cast-steel. Through these clamp-jaws and below the rails passes the bolt 14, having at one end a head 16 and at the other end a nut 17, preferably bearing against a washer 18. This nut 17 may be secured in the desired position by a cotter 19 of ordinary construction or equivalent mechanism. Some other device— as, for instance, a turnbuckle having the tension properties of a bolt—may be substituted for the bolt without departing from the broad principle of our invention, and in the same way other means of tightening the bolt than the nut may be used.

Between the rails 10 and 11 is a fairly broad main spacing-block or separator 20, preferably having depending from it a loop 21, embracing the bolt 14, so that the block will not slip lengthwise of the rails. We also provide three narrower spacing-blocks or separators 22, 23, and 24, of different widths, so that each one when used between the rails with block 20 will make the distance between the rails different from what it is when another of the three blocks is so used. The rails may be used with one, two, or three of these blocks 22, 23, and 24 between the rails, as desired. The blocks not so used between the rails are always placed outside the rails, as shown, so that whatever the location of these three blocks, as just indicated, the total thickness of spacing-blocks 20 22 23 24 and the webs 25 and 26 will be a constant quantity.

In the preferred form of construction the two clamp-jaws 15 are made just alike, preferably from the same pattern, and have lower arms 27 meeting at 28, a fixed distance below the center-line A of bolt 14, the center of pressure being in the line B B. These clamps also have upper arms 29, bearing against the combined spacing-blocks and rail-webs described in the last paragraph above, the center of pressure being in the line C C, which is substantially as far from line A as line B B is, so that the strain produced by tightening bolt 14 is communicated equally to the upper and lower arms just described, and as the horizontal length of the two arms 29 and the combined thickness of blocks 20, 22, 23, and 24 and webs 25 and 26 is equal to the length of

the two lower arms 27 taken together this relation is practically undisturbed as the bolt is tightened.

It is manifest that if the adjustable feature 5 is not desired the blocks 22, 23, and 24 may be entirely omitted and the proportions of the block 20 and the lengths of arms 15 be readjusted in the making, so as to make up for their absence, the block 20 filling the entire 10 spacing distance between the rails and the arms 29 bearing directly against the other sides of the webs of the rails. It is also manifest that by properly proportioning the parts for strength the distance from the lines A to 15 B and A to C may be varied as the whim of the designer may dictate without departing from the broad principle of our invention.

One particular advantage obtained by the construction herein described is that it is unnecessary to bore holes in the rails, an expensive process when the rails are in place and trains are passing frequently.

In the operation of our invention we have all the parts which are shown in the drawings made by usual processes and take them to the place where the guard-rail is to be applied to a main rail. If the spacing of rails shown in the drawings is the one desired, we arrange all the parts as shown in the drawings and tighten the bolt 14 until everything is secure. If it is desired to place the rails farther apart, we transpose spacers 23 and 22, and if a narrower spacing is desired we transpose spacers 24 and 22, of course loosening or 35 removing the bolt 14 while the substitution is being made.

We do not wish to be understood as limiting ourselves to the details of construction described and shown. These may be varied 40 within reasonable limits without departing from the spirit of our invention.

Having thus described our invention, what we claim as new, and desire to secure by Letters Patent, is—

45 1. In a rail-clamp, in combination with the rails to be clamped, one or more spacing-blocks between or adjacent to the webs of said rails, a pair of clamp-jaws each bearing against said combined rail-webs and spacing-block or blocks, passing around the outside of the rail and meeting the other jaw below the rail, and means connecting said jaws between the said bearing-points and below the rails for tightening said jaws, for the purposes set forth.

50 2. In a rail-clamp, in combination with the rails to be clamped, one or more spacing-blocks between the webs of the rails, a bolt below the rails, a pair of clamp-jaws on said bolt, having upper arms bearing against the

combined spacing block or blocks and rail-webs, and lower arms bearing against each other at a point below said bolt, the total length of the upper arms, spacing block or blocks and rail-webs being approximately the 65 sum of the length of the two lower arms, for the purposes set forth.

3. In a rail-clamp, in combination with the rails to be clamped, a series of transferable spacing-blocks adjacent to the webs of said rails, a bolt passing below said rails, and a pair of clamp-jaws on said bolts, having upper arms bearing against said combined spacing-blocks and rail-webs and lower arms bearing against each other at a point below said 70 bolt, the total length of the upper arms, spacing-blocks and rail-webs being approximately the sum of the length of the lower arms, for the purposes set forth.

4. In a rail-clamp, in combination with the rails to be clamped, a series of transferable spacing-blocks between and adjacent to the webs of said rails, a bolt passing below said rails and a pair of clamp-jaws on said bolts, having upper arms bearing against said combined spacing-blocks and rail-webs, and lower arms bearing against each other at a point below the center line of the bolt, approximately equal to the distance the center of the spacing-blocks and rails is above the center of the bolt, for the purposes set forth.

5. In a rail-clamp, in combination with the rails to be clamped, a series of transferable spacing-blocks between and adjacent to the webs of said rails, the total thickness of the webs of the rails and the spacing-blocks being substantially the same in all positions of the spacing-blocks, a bolt passing below the flanges of said rails, a pair of clamp-jaws on said bolts, having upper arms bearing against 85 said combined spacing-blocks and rail-webs, and lower arms bearing against each other at a point below the center of the bolt, substantially equal to the distance of the center of the spacing-block from the center of the bolt, 90 for the purposes set forth.

6. In a rail-clamp, in combination with the rails to be clamped, the spacing-blocks 20, 22, 23, and 24, the bolt 14 below the rails, the clamp-jaws 15, having the upper arms 29 bearing against the combined spacing-blocks and rail-webs and the lower arms 27 bearing against each other, all of the parts being arranged and disposed substantially as shown and described, for the purposes set forth. 105
